UNITED STATES PATENT OFFICE.

EDWARD L. NUGENT, OF CHARLESTON, WEST VIRGINIA.

SWITCH.

No. 841,337.

Specification of Letters Patent.

Patented Jan. 15, 1907.

Application filed April 21, 1906. Serial No. 313,069.

To all whom it may concern:

Be it known that I, EDWARD L. NUGENT, a citizen of the United States, residing at Charleston, in the county of Kanawha and State of West Virginia, have invented a new and useful Improvement in Switches, of which the following is a specification.

This invention relates to switches, and more particularly to switch-operating devices, the object being to provide a very novel device which can be readily attached to the ordinary switch now in use.

Another object of my invention is to provide a device which is very simple and cheap in construction and one which is very effective in use, as the switch can be operated from the engine.

Another object of my invention is to provide a very simple tripping device which is adapted to be connected to the engine, so that the switch can be operated as desired by the engineer.

With these objects in view the invention consists of the novel features of construction hereinafter fully described, and pointed out in the claims.

In the drawings forming a part of this specification, Figure 1 is a plan view of the track and siding, showing my improved switch-operating device in place. Fig. 2 is a longitudinal sectional view of the same. Fig. 3 is a detail view. Fig. 4 is a section taken through the track, showing the tripping-rod in engagement with one of the operating-arms. Fig. 5 is a perspective view of the tripping device.

In the drawings, A indicates the main track, and B the side track, which are connected together by the ordinary switch C. The points C' of the switch are connected to the bar D, carried by a crank E, formed on the lower end of the vertical shaft E, mounted in a plate F, secured between the ties. A pulley F' is mounted on the upper end of the shaft E, so that the switch can be operated in the ordinary way, if desired.

A disk G, provided with a central square opening, is mounted on the square portion of the shaft E, provided with spaced openings in which the ends of the rods H, I, J, and K are pivotally connected, provided with bifurcated ends H', I', J', and K', in which the crank-arms of the shafts H² I² J² K² are secured, which are mounted in bearings H³, I³, J³, and K³, arranged between the ties of the track. The shafts H² I² are provided with

arms H⁴ I⁴ at their ends, arranged between the main track and the shafts J² K², extending over into the side track B, having arms J⁴ K⁴ at their ends and arms J⁵ K⁵ intermediate their ends between the main track for the purpose hereinafter fully described.

In Fig. 5 I have shown my improved tripping device, which is adapted to be carried by the pilot of the engine, and consists of a crank-arm L, mounted on a shaft L', provided with a bifurcated lower end L², the walls of said bifurcation being slotted, in which the pin M' of the bar M is adapted to work. The bar is adapted to be supported in guide-brackets N between the rails and is provided with downwardly-projecting ends M², adapted to engage the arm of the shafts H², I², J², and K². The other end of the crank-arm L is secured in the bifurcated end 75 of the rod O, which is connected to a lever O', provided with a hand-grip mounted in a frame P' of a plate P, which is adapted to be secured in the cab of the engine and is provided with a segmental rack P², adapted to 80 be engaged by the lever, so as to lock the arm in any position desired.

From the foregoing description it will be readily seen that I have provided a switch-operating device which can be operated 85 from the engine, so as to cause the engine to follow the main track or side track or so that the engine can return from the side track, as by throwing the bar M of the tripping device into engagement with the arms of the shafts 90 95 the points will be opened and closed, as desired.

Having thus fully described my invention, what I claim as new, and desire to secure by Letters Patent, is—

1. In a device of the kind described, the combination with switch-points carrying a rod, of a crank-shaft connected to said rod, a disk fixed on said shaft, rods connected to said disk and crank-shafts connected to said rods provided with arms, for the purpose described.
2. In a device of the kind described, the combination with switch-points connected together by a rod, a crank-shaft connected to said rod, a disk fixed on said shaft, rods connected to said disk and crank-shafts connected to said rods provided with arms for the purpose described.
3. In a device of the kind described, the combination with a switch, of a rod carried by the points of said switch, a crank-arm connected to said rod, carried by a shaft, a

disk mounted on the shaft, rods connected to said disk, shafts provided with arms connected to said rods and means carried by the engine for engaging said arms, for the purpose described.

4. In a device of the kind described, the combination with switch-points carrying a rod, of a shaft provided with a crank connected to said rod, a disk mounted on said shaft, shafts mounted between the tracks provided with arms at each end, rods connecting said arms to said disk, and tripping means carried by the engine, for the purpose described.

5. In a device of the kind described, the combination with switch-points carrying a rod, of crank-shafts mounted between the ties to each side of said points, arms projecting upwardly from each shaft between the ties, a crank-shaft mounted to one side of said points provided with a disk, and connected to the rod carried by the points, and rods connecting said disk to the crank-shafts arranged between the ties, for the purpose described.

25 6. In a device of the kind described, the

combination with switch-points, of a crank-shaft connected to said points provided with a disk, crank-shafts provided with arms mounted to each side of said points, rods connecting said shafts to said disk, and a crank carrying a rod adapted to engage said arms, for the purpose described.

7. In a device of the kind described, the combination with a switch, of a rod carried by the points of said switch connected to a shaft arranged to one side, a disk mounted on said shaft, crank-shafts provided with arms at their ends arranged between the tracks to one side of said points, rods connecting said shafts to said disk, crank-shaft mounted between the rails and siding provided with upwardly-projecting arms, rods connecting said shafts to said disk, and tripping means carried by the engine adapted to engage said arms, for the purpose described.

E. L. NUGENT.
